(57) **CLAIM**

The ornamental design for speaker with extendable top, as shown and described.

DESCRIPTION

FIG. 1 is a perspective view of the current embodiment of speaker with extendable top embodying the new design in the closed position;

FIG. 2 is a perspective view thereof in the extended position;
FIG. 3 is a top view thereof;

FIG. 4 is a bottom view thereof;

FIG. 5 is a front view thereof in the closed position;

FIG. 6 is a right side view thereof;

FIG. 7 is a left side view thereof;

FIG. 8 is a rear view thereof;

FIG. 9 is a front view thereof in the extended position; and,
FIG. 10 is a rear view thereof.

The broken lines shown in the drawings represent unclaimed portions of the speaker with extendable top and form no part of the claimed design.
